M. G. Benjamin
INVENTOR.

UNITED STATES PATENT OFFICE

MERRILL G. BENJAMIN, OF LAKewood, OHIO

POWER INSTRUMENT AND METER

Application filed February 16, 1928. Serial No. 254,915.

The present invention relates to improvements in power indicators, instruments and meters used in connection with power consuming and power-producing apparatus, particularly steam boilers, for indicating and metering the various operating functions and conditions of said apparatus, for example, the drafts in the various portions of the combustion chamber and passes of a steam boiler furnace, the quantities of steam generated, and the fact that fuel feeding mechanism is in operation, or otherwise, together with its approximate speed, and whether or not a positive pressure exists in the combustion chamber of the boiler furnace. Other functions such as the steam pressure, temperature and rate of flow, together with combustion chamber and flue gas temperature are to be considered as within the scope of this invention pertaining to metering apparatus; also the position of dampers, valves and other movable elements of said power unit.

The invention is illustrated as embodied in the instrument board of a steam boiler and furnace and consists of a small scale diagrammatic model of the main unit made, as far as practicable, to look like the main unit and appear in operation as the main unit would appear could an observer see the entire unit and its operative elements at one time.

The novel feature of this invention consists in the diagrammatic unit, and the advantages claimed are that an operator of the usual type not familiar with technical matters and incapable of intelligently interpreting the indications of the usual indicators in their true significance can readily judge, by the indications visible on the diagrammatic unit, the exact condition existing in the main unit.

In subsequent applications, the inventor will describe novel means for recording the indications made on the diagrammatic unit, together with novel means for controlling the operation of the main unit from movable elements connected with the diagrammatic unit.

In the drawings, which represent the preferred embodiment of the invention, the single figure represents a cross-section view 50 of a steam boiler and furnace unit, together

with a diagrammatic representation of the same unit.

In the illustrated embodiment of the invention, a steam boiler and furnace unit is indicated generally by reference numeral 1. The diagrammatic representation of said unit is indicated generally by reference numeral 2. Ordinarily, a steam-boiler unit includes auxiliaries, such as forced-draft fans, economizers, preheaters, etc., but for the purpose of illustrating this invention the drawings have been made as simple as possible to avoid confusion, and only one such auxiliary or element has been shown. In the case of the diagrammatic representation, the numerals applied to the parts of the unit are the same as in the original unit, in order to make the drawing readily intelligible. The steam boiler and furnace unit consists of a steam boiler 3, and its furnace 4.

The boiler is shown provided with an induced draft fan 5 driven by an electric motor 6, having starting switches 7. The starting switches are indicated here only diagrammatically because they are common and well understood by those versed in the art. Means for varying the speed of the induced-draft fan motor is indicated by rheostat 8. The steam outlet of the boiler is indicated by a pipe 9 in which is located a metering Venturi tube nozzle, or orifice of a type common in such practice, indicated by reference numeral 10. A means of measuring the steam output of boiler is indicated by the combination of the above mentioned Venturi tube, or orifice, 85 its connecting tubes 11 and 12 and U tube 13, having the usual scale by which the level of the mercury in the tube may be read.

In the diagrammatic unit the combustion chamber 4 is sealed by a lining 14, which has an opening 15 communicating to the atmosphere. The side of diagrammatic combustion chamber 4 presented to view, is covered with glass or other transparent material. A small pipe connection 16 is shown for the purpose of conducting steam or other visible vapor into the sealed combustion chamber 4. Also connecting the combustion chamber 4 of the diagrammatic unit with the combustion chamber 4 of the main unit is the pipe 17.

It will be understood by those skilled in the art that I have provided a model or diagrammatic representation of a boiler connected to an actual, operating boiler in such manner that the combustion chamber draft in the diagrammatic unit will be equal for practical purposes, to the pressure in the combustion chamber of the main unit.

Now, for purposes of operation, it is desirable to have the combustion-chamber pressure as near zero, or neutral, as possible, to prevent the excess infiltration of air into the furnace, and also to prevent the escape of the gases of combustion through openings in the combustion chamber into the room or space enclosing the furnace. In the device shown, the pipe 17 communicates the combustion-chamber pressure in the main unit to the diagrammatic unit. The opening 15 permits the gases introduced through the pipe 16 to escape to the atmosphere, if the combustion-chamber pressure is positive, and also permits outside air to enter and equalize the combustion chamber pressure in case it is negative. In order to make the condition of positive or negative pressure evident to an operator, steam or visible vapor is conducted into combustion chamber 4 by means of pipe 16. It will then be evident to the operator, if vapor is escaping from vent 15, that the combustion chamber pressure is positive and an adjustment of draft condition is necessary. The draft is increased, accordingly, until the vapor no longer escapes from opening 15, indicating that the proper condition exists for the satisfactory operation of the main unit.

The means above described for the observation of one function of a boiler is, obviously, only one means of accomplishing the same result. In a practical installation, however, a number of such functions will require observation. It is, therefore, the intent of this invention to cover any and all means of accomplishing the result described, for any and all functions of power units, as far as it may be desirable to apply them.

In general, the operativeness, connection to power lines, rate of speed, position of dampers, valves and other working or moving elements of power units is intended to be indicated on the diagrammatic unit by means generally described as follows.

The driving motor for the induced-draft fan 5 is represented by numeral 6. It is shown connected through its starting switches 7 and controlling rheostat 8 to a main power circuit 18 by conductors 19. The shunt field of the motor 6 is indicated by the coil 20. Across an auxiliary rheostat 31 operated by and mechanically connected to rheostat 8 is connected motor 6 of the diagrammatic unit by means of conductors 21. It will be evident to those skilled in the art that the voltage drop across the rheostat will be communicated to the motor 6 of the diagrammatic unit, and that its

speed will, therefore, be approximately proportional to that of the corresponding element of the main unit. It will be observed that the motor 6 of the diagrammatic unit is shown as a series motor which will, therefore, be responsive in speed to the voltage impressed across its terminals.

While the above described motors and connections provide an operative system, various other methods of connections between the main driving motor and the diagrammatic motor may be used. For instance, the main driving motor may be an alternating current motor of the wound rotor type having connected to its shaft a generator so wound that the voltage produced would be in proportion to its speed. Connected to this generator on the diagrammatic unit might be a motor so wound to respond in speed directly to the voltage applied across its terminals. There are other obvious means of obtaining the desired result and all such are to be considered within the scope of this invention.

A damper 22 is shown in the connection between furnace outlet and fan 5. This damper in the main unit is shown having a mechanical connection generally indicated by rods 23 and 24, to a corresponding element in the diagrammatic unit. This invention is intended to cover, however, any and all other means of connection between said dampers which might prove applicable to a practical installation. The position of main damper is thus indicated to the operator by means of the diagrammatic damper on the small scale unit.

For further indicating conditions within the power unit on the diagrammatic unit, another means is provided in the form of a periscope 25. This device consists of a tube placed in the setting of boiler furnace at a point where the condition of the furnace gases may be observed, for example as to smoke. In the opposite wall of said furnace is placed a powerful electric lamp 26 shown connected to source of current 18 by conductors 27. The tube of periscope 25 is connected to the diagrammatic unit by means of reflectors 29 and connecting tubing 30. It is obvious that, by looking into the tube 28, the lamp 26 will be visible and that any cloud of smoke or dust will affect the brilliancy of said lamp and be an indication of the condition of the furnace gases at this point. While the described method of presenting an indication of conditions in the power unit is a practical one, it is the purpose of this invention to cover any and all means of communicating such indications from a power unit to a diagrammatic unit or portion thereof.

The method of indicating the magnitude of some functions of the power unit on the diagrammatic unit is generally indicated by the Venturi tube 10 and the U tube 13. U tube 13 may be diagrammatically connected to Venturi tube 10 of diagrammatic unit but is

operatively connected by tubes 11 and 12 so that the flow of steam from the main boiler will cause a depression in one leg of the U tube and a corresponding elevation in the other leg of the tube. By means of a properly calibrated scale a reading of the rate of flow of steam may be obtained.

5 The term "operative connection," used herein, is intended to define any connection such as piping, electric wiring, levers or relay system whereby a force or movement is transmitted between the apparatus connected.

10 For the sake of simplicity the drawings have been made largely diagrammatic. It is to be understood, however, that the invention is not limited to its preferred embodiment but that the various instrumentalities diagrammatically illustrated may be variously constructed, and that the invention may be 15 embodied in other structures within the scope of the invention as defined in the following claims.

I claim:

1. The combination with a steam boiler and 20 furnace and a diagrammatic representation thereof, of means for indicating on said diagrammatic representation, the conditions in said boiler and furnace, and means for controlling said indicating means in accordance with variations of said conditions.

2. The combination with a boiler and furnace having auxiliaries, such as an induced-draft fan, a diagrammatic representation of said boiler and furnace including 35 models of said auxiliaries, of means for operatively connecting said models to said auxiliaries whereby said models indicate the speeds or conditions of said auxiliaries.

3. The combination with a furnace and a 40 diagrammatic representation thereof, of means on said diagrammatic representation for indicating the operating conditions in said furnace by similar conditions in the diagrammatic representation and operative 45 connections between said furnace and said indicating means.

4. The combination with a steam-producing 50 unit, of means for measuring the steam flow therefrom, a diagrammatic representation of said unit including diagrammatic measuring means and actual steam-flow indicating means and operative connections between said steam-flow measuring means and said steam-flow indicating element on said 55 diagrammatic representation.

5. The combination with a boiler furnace, 60 a diagrammatic representation of said furnace, means for registering an indication of a condition of said furnace, means for transmitting said indication to said diagrammatic representation and means for registering a similar indication on said diagrammatic representation, to make the processes taking 65 place in the main unit observable on a cor-

responding portion of diagrammatic representation.

6. The combination with a power-producing unit, of a diagrammatic representation of parts of said unit, means for indicating on said diagrammatic representation, the conditions existing in said unit, an operative connection between said diagrammatic representation and said unit and means for causing the conditions existing in said unit to set up a similar condition in said diagrammatic representation.

7. The combination of a power-producing or power-consuming unit, a diagrammatic representation of one or more operative portions of said power unit, an operative connection between one or more operative portions of said unit and the corresponding portions of said diagrammatic unit, whereby any change in the position of or the relation between said portion and any other portion of said power unit, will cause a similar change in the position or relation of the corresponding portion of the diagrammatic unit.

8. The method of power metering which 90 consists in operatively connecting one or more elements of a main power unit to similar elements of a diagrammatic unit in such manner as to cause a visible representation of conditions existing in the main power unit to appear in the diagrammatic unit.

9. In a system of metering for power-producing or power-using apparatus, a diagrammatic unit so constructed that the various operative elements or functions of the main unit are diagrammatically represented thereon, and means for causing the elements or functions of said unit to present a visible indication of the true or relative value of similar elements or functions in said apparatus.

105 In testimony whereof, I have hereunto set my hand.
